(57) CLAIM

The ornamental design for a cigar, as shown and described.

DESCRIPTION

FIG. 1 is a front elevational view of a cigar showing my new design;

FIG. 2 is a rear elevational view thereof;

FIG. 3 is a left side elevational view thereof, the right side being a mirror image; and,

FIG. 4 is a bottom plan view thereof, the top being a mirror image.

The broken lines shown in FIGS. 1-4 are for illustrative purposes only, and form no part of the claimed design.
